UNITED STATES PATENT OFFICE.

WILLIAM M. MOSER, OF PHILADELPHIA, PENNSYLVANIA.

DESIGN FOR AN OPEN-WORK CURTAIN.

No. 39,496.

Specification for Design.

Patented Sept. 1, 1908.

Application filed June 18, 1908. Serial No. 439,259. Term of patent 3½ years.

To all whom it may concern:

Be it known that I, WILLIAM M. MOSER, a citizen of the United States, residing at Philadelphia, in the county of Philadelphia and State of Pennsylvania, have invented a new, original, and ornamental Design for Open-Work Curtains, of which the following is a specification, reference being had to the accompanying drawing, forming part thereof.

The figure is a plan view of an open-work curtain showing my new design.

I claim:

The ornamental design for an open-work curtain as shown.

WILLIAM M. MOSER.
